WIRE FENCE MACHINE

Harry L. Kitselman, Muncie, Ind., assignor to
 Indiana Steel & Wire Company, Muncie, Ind.,
 a corporation of Indiana

Application April 1, 1939, Serial No. 265,411

18 Claims.

(Cl. 140—4)

This invention relates to the manufacture of wire fabric, such as poultry netting, and more particularly to the manufacture of that type of fabric known as "straight-line" netting embodying straight line wires and mesh wires each of which is secured, as by twisting, alternately to two adjacent line wires.

The invention has for its primary object the production of a machine capable of manufacturing wire fabric of graduated mesh—i. e., fabric in which the width of the mesh varies from one edge of the fabric to the other. More specifically, it is my object to construct a machine capable of producing graduated-mesh fabric in which the variation in the width of the mesh may have any desired extent.

A further object of my invention is to facilitate the production of fabric having a relatively fine mesh, at least over a part of its transverse extent.

Another object is to simplify the operation of stripping finished netting from a machine of the type referred to.

Still another object is to prevent distortion of the mesh-pattern as the result of tension imparted to the fabric-wires while they are being twisted together to form locks.

In carrying out my invention, I may employ a machine of the general type set forth in my prior Patent No. 2,053,221, granted September 1, 1936. In that machine, the fabric is formed on the face of a movable carrier, desirably a rotating drum, which bears an endless series of rows of twisting gears adapted to form the locks in the fabric. The mesh wires of the fabric are fed on to the face of the carrier, shifted alternately in opposite directions into the desired pattern as the drum rotates, and deposited in the twisting gears, the shifting means comprising wire-engaging abutments, preferably in the form of pins, arranged in rows on opposite sides of each set of twister gears and shifted in predetermined manner to produce the desired mesh pattern as the carrier moves. When the mesh wires have been deposited in the slots of the twister gears, the line wires are fed into such slots, and the twister gears then rotated to twist the line wires and mesh wires together, after which the finished fabric is stripped from the drum.

While a machine of this general type is preferred and while the specific embodiment of my invention described herein employs such a machine, it is to be understood that my invention is not limited thereto; as certain of the benefits of my invention are obtainable whether the mesh

wires are formed into the desired pattern before or after entering into association with the carrier which bears the twister gears or other lock-forming devices.

In embodying my present invention in a machine of the type shown in my prior patent, the twister gears in each row are spaced at graduated distances apart to correspond to the graduated mesh of the fabric which it is the primary object of my invention to produce. The wire-shifting pins are correspondingly spaced, so that, at the conclusion of their wire-shifting movement they will be in approximate alignment with the respective twister gears. The pins associated with each set of twister gears have a common support and therefore all move laterally through the same distance as the fabric is formed. The distance through which the pins move must be approximately equal to half the width of the coarsest mesh; and, as a result, each of the closely spaced pins which produce fine-mesh fabric may pass one or more twister gears before coming into alignment with that one into which it is to deposit a wire. To prevent the more closely spaced pins from depositing wires in twister gears other than those with which they ultimately come into alignment, I may defer feeding the closely spaced mesh wires to the carrier until after each of the closely spaced pins has passed the twister gear next adjacent to the one in which it is to deposit the wire it is shifting.

After the shift pins deposit the mesh wires in the twister-gear slots they continue their movement for a short distance to create in each mesh wire a slight amount of slack which is later taken up in the twisting operation. The pins are next retracted to open the gear-slots for deposition of the line wires therein, the line wires are deposited, and the pins are again advanced to create slack in the line wires. The pins are then retracted and held in position corresponding to the corners of the mesh while the twister gears are rotated to form the locks in the fabric, the presence of the pins in the corners of the mesh preventing any distortion of the fabric as a result of the twisting operation. Following formation of the locks, the pins are retracted another step out of the mesh-corners, and the finished fabric is then stripped from the drum.

In order to make practicable the formation of fabric having a relatively narrow mesh, I may offset or stagger axially the teeth of adjacent twister gears whereby adjacent gears may be spaced apart a distance less than their outside diameter.

To strip the finished fabric from the carrier, I mount adjacent the carrier a stripping roll provided with a multiplicity of outwardly extending fingers positioned to be received by the corners of the mesh of the fabric. I drive this stripping roller by mechanism including a slipping clutch, or other yielding device, which tends to impart to the stripping roll a peripheral speed somewhat greater than the speed of the carrier. As a result, the fingers on the stripping roll catch in the corners of the mesh of the fabric and pull the fabric from the slots in the twister gears.

The accompanying drawings illustrate my invention: Fig. 1 is a front elevation of a complete machine with parts thereof broken away and illustrated in vertical section; Fig. 2 is an end elevation of the machine showing driving mechanism for the stripper-roll and take-up device; Fig. 3 is a vertical section through the machine; Fig. 4 is a fragmental development of the drum surface showing the action of the shifter pin forming the mesh; Fig. 5 is a development of the cams which operate the wire-shifting mechanism and the twister gears; Figs. 6 and 7 are an elevation and a section respectively showing means employed for holding shift-rods on the face of the drum; Fig. 8 is a fragmental axial section illustrating the arrangement of twister gears employed to form the finer-mesh portions of the fabric; Fig. 9 is a tangential section on the line 9—9 of Fig. 8; Fig. 10 is a fragmental plan view of the stripper roll; Figs. 11 to 14 are elevations of a row of shift pins showing successive positions thereof; and Figs. 15 to 18 are inter-related views illustrating the considerations which influence the location at which the second set of mesh wires is fed to the carrier.

In the machine shown in the drawings, the fabric-carrier is in the form of a drum supported by and rotatable with a shaft 20 mounted at its ends in suitable bearings in a frame 21. Secured to the frame 21 and extending inwardly along the shaft 20 from the opposite ends thereof are two drum cams 22 and 22', the inner ends of which may be provided with bearings 23 lending additional support to the shaft 20. Between the two drum cams 22 and 22' there are rigidly secured to the shaft 20 a plurality of axially spaced spiders one of which, indicated at 24, is disposed adjacent the inner end of the drum-cam 22, and another of which, indicated at 24', is disposed adjacent the inner end of the drum-cam 22'. Each of the spiders is provided with an annular series of notches for the reception of two series of longitudinally extending supporting members 25 and 25'.

The supporting members 25 are arranged alternately with the supporting members 25', the former extending from the spider 24' past the spider 24 and over the drum-cam 22, and the latter extending from the spider 24 past the spider 24' and over the drum-cam 22'. Rotatably mounted on the outer end of the drum cam 22 is a gear 26 to which the adjacent ends of the supporting members 25 are secured. A similar gear 26' on the drum cam 22' provides a support for the adjacent ends of the supporting members 25'.

Each of the supporting members 25 is provided adjacent the inner face of the spider 24 with a boss 27 in which there is mounted an axially extending dowel pin 28 which projects into a recess in the inner face of the spider 24. The ends of each of the supporting members 25 are secured to the gear 26 and spider 24' respectively, 75 as by means of screws. When these screws are

removed, the supporting member may be moved axially to withdraw the dowel pin 28 from the spider 24, whereupon the supporting member 25 can be removed from the machine. The supporting members 25' are similarly mounted, having a dowel-pin connection with the spider 24' and having their ends secured to the spider 24 and the gear 26' respectively.

In addition to aiding in the mounting of the members 25 and 25', the bosses 24 serve to transmit to the spiders the axial thrust resulting from shifting of the mesh wires and from actuation of the twister gears. This thrust is transmitted to the frame of the machine through thrust bearings 29 acting between each of the end spiders 24 and 24' and the respectively adjacent drum cams 22 and 22'.

Means for rotating the drum is shown in the drawing as comprising a drive-pinion 30 meshing with a gear 31 which is rigidly mounted on the shaft 20 at one end of the machine. The gear 31 meshes in turn with a pinion 32 rotatable with a countershaft 33 which extends for the length of the machine and which, at its opposite end, carries a pinion 34 meshing with a gear 35 on the shaft 20. In addition to the pinions 32 and 34, the shaft 33 also carries pinions 36 which mesh with and drive the gears 26 and 26'.

Each of the supporting members 25 and 25' is provided in its outer surface with a pair of circumferentially spaced grooves which receive respectively two parallel plates 40 extending axially of the machine from the spider 24 to the spider 24'. Between each pair of plates 40 there are supported a series of twister gears 41 arranged in a row extending from one end of the drum to the other. Conveniently, the twister gears 41 of each row are arranged in groups individually removable from and insertable in the machine. To this end, the twister gears of each group are provided with hubs rotatably received in openings in a pair of opposed plates 44, as more fully described in my prior patent above referred to. The several pairs of plates 44 are individually mounted between the plates 40, so that any pair, together with the associated group of twister gears, can be separately removed and replaced.

The twister gears are all of uniform diameter and each has an annular series of teeth 45 meshing with a rack 46 which is supported for axial sliding movement on the outer surface of the associated supporting member 25 or 25' between the plates 44. Each twister gear is provided in known manner with a radial slot 47 adapted to receive two or more of the wires of which the fabric is formed and to twist such wires together when the gear is rotated. In the normal position of each gear, the slot therein is in alignment with radially extending slots which open in the outer edges of the plates 40 and 44.

In each row of twister gears, the several gears are spaced apart at distances corresponding to the widths of the various meshes in the wire fabric which the machine is to produce. In the machine shown, four different widths of mesh are provided, the narrower mesh being formed at the left-hand side of the drum (Figs. 1 and 4), and the wider mesh at the right-hand side of the drum. By way of example, I have used the machine shown in the drawings to produce fabric having graduated meshes of $\frac{1}{8}$ of an inch, 1 inch, $1\frac{1}{4}$ inches and 2 inches in width. Each row of twister gears, therefore, will include a set, located at the left-hand end of the drum, 75

spaced $\frac{1}{8}$ of an inch apart, a second set spaced 1 inch apart, a third set spaced $1\frac{1}{4}$ inches apart, and a fourth set spaced 2 inches apart.

To prevent the closest spacing of the twister gears from unduly limiting the diameter of such gears, the teeth 45 of the adjacent twister gears producing the finer-mesh fabric may be offset axially as indicated at the left in Figs. 8 and 9. Thus, the diameter of the twister gears may exceed the width of the finest mesh of the fabric.

For the purpose of forming the mesh wires of the fabric into the desired pattern, I mount on opposite sides of each row of twister gears a pair of shift rods 50 each of which carries a series of axially spaced wire-shifting pins 51 projecting radially outward beyond the plates 40. The spacing of the pins 51 corresponds to the spacing of the associated set of twister gears, as is clear from Fig. 1. The shift rods 50 associated with each supporting member 25 extend outwardly beyond the spider 24, where they are joined to each other and to a common shank 52 secured to a head 53 which is slidably mounted on the projecting end portion of the supporting member 25. Desirably, each of the shanks 52 is screw-threaded, extends through the head 53, and is provided on opposite sides of such head with nuts by means of which the relative axial position of the head and shank can be adjusted.

On the inner side of each of the heads 53, I mount a cam-following roller 54 received in a cam groove 55 in the drum-cam 22.

The shift rods 50 associated with the supporting members 25 are similarly adapted for attachment to heads 53' which slide on the projecting portions of the supporting members 25' and carry cam-following rollers 54' received in a cam-groove 55' in the drum-cam 22'.

The various shift rods 50 are slidably supported upon the rotatable drum, conveniently by some such means as that illustrated in Figs. 6 and 7. As is clear from those figures, there is provided between adjacent shift rods 50, where they cross one or more of the spiders 24, a keeper 56 which is secured to the drum, as by means of screws 57. Each keeper 56 has on its opposite sides flanges 56' which overlie the adjacent shift rods 50 and hold them against the face of the drum. To prevent the keepers 56 from interfering with wire-shifting movement, their outer surfaces are approximately flush with the outer surfaces of the rods 50, the adjacent outer edges of such rods being grooved for the reception of the flanges 56'. If necessary, the opposed faces of the adjacent rods 50 may be relieved to make room for the body of each keeper 56, the length of such relief being such that the shoulders at its ends will not interfere with the necessary shifting movement of the rod 50.

For the purpose of actuating the twister gears, the racks 46 associated with the supporting members 25 extend outwardly to the left beyond the spider 24 and head 53 where they are connected respectively to heads 58 slideable on the projecting portions of the supporting members 25. Desirably the connection of each rack 46 to its associated head 58 is an adjustable connection so that the relative axial positions of the rack and head can be varied. Mounted on the inner side of each of the heads 58 is a cam-following roller 59 received in a cam-groove 60 in the drum-cam 22. The racks 46 associated with the supporting members 25' are similarly connected to heads 58' carrying cam-following

rollers 59' which are received in a cam-groove 60' in the drum-cam 22'.

Each of the mesh wires 65 of the fabric is fed on to the rotating drum, engaging the outer edges of the plates 40 between two adjacent twister gears. Each wire is deflected laterally of itself, first in one direction into the slot of a twister gear on one side of it and then in the opposite direction into the slot of a twister gear on the other side of it. The wires are fed on to the drum under tension so that they tend to enter the slots in the twister gears when they come into alignment therewith. I find it of advantage, however, to slope the pins 51 outwardly of the drum in the direction of their wire-shifting movement so that each of them will exert on its associated wire a force having a downward component aiding the wire in entering the twister-gear slot.

The action of the shifter pins in deflecting the mesh wires into the desired pattern is indicated in Fig. 4, which illustrates a developed portion of the surface of the drum on which the fabric is formed and also a diagrammatic development of the two cam-grooves 55 and 55' which operate the shift-rods 50. In Fig. 4, the drum-surface is assumed to move upwardly. Alternate sets of shifter pins beginning with the lowermost set shown are mounted on shift rods 50 which extend leftwardly beyond the end of the drum and are moved by co-operation between the cam-following rollers 54 and the cam groove 55; while the other sets of shifter pins are mounted on rods 50 which extend rightwardly from the drum and are moved by co-operation between the cam-following rollers 54' and the cam groove 55'.

In Fig. 4, the lowermost pair of shift-rods 50 are shown in their normal positions, the cam-follower 54 which actuates them occupying a dwell in the cam-groove 55. The next pair of shift rods 50 are also in normal position, their cam-follower 54' occupying a dwell in the cam-groove 55'. The two dwells just referred to are circumferentially co-extensive and terminate at the points marked A in Fig. 4.

Beyond the dwell terminating at A each cam-groove has an outwardly inclined portion A-B leading into a second dwell B-C. The axial extent of each cam-groove portion A-B is sufficient to carry each pair of shift-pins 51 far enough past the slot in the associated twister gear to create a slight amount of slack in the mesh wires 65. Because of the over-travel of the pins, as well as because of their inclination and of the necessity for clearance between the outer ends of the pins and the mesh-wires entering into association with the drum, the axial extent of each cam-groove portion A-B must be somewhat greater than one-half the distance between adjacent twister gears at the right-hand end of the drum where the coarsest mesh of the fabric is formed.

In Figs. 11 to 14, I have shown in elevation the left-hand portion and right-hand portion of a row of twister gears, the twister gears at the left being spaced closely apart to produce the fine-mesh portion of the fabric and the twister gears at the right being widely spaced to produce the coarse-mesh portion. The shift rod 50 illustrated bears a series of spaced shift pins 51 each of which constitutes one of a pair, the other pin of each pair being correspondingly positioned on a second shift rod 50 on the opposite side of the row of twister gears. For convenience of

description, I have given the various twister gears and shift pins shown in Figs. 11 to 14 different reference characters, the closely spaced twister gears being identified as 41a, 41b etc., and 5 5 the widely spaced twister gears being identified as 41y and 41z. The shift pins have been correspondingly individually identified as 51a, 51b, 51y and 51z.

10 The normal position of each shift pin is illustrated in Fig. 11, while the position of the shift pins at the conclusion of their wire-shifting movement is indicated in Fig. 14. In this shifting movement, the shift pin 51y comes into engagement with a mesh wire 65, previously fed 15 on to the drum to the left of the shift pin, carries that mesh wire along the top of the plates 40 into the slot of the twister gear 41y, and then continues for a short distance to create the slack previously referred to.

20 It will be noted from Fig. 11 that if the mesh wires entering into the fine-mesh portion of the fabric were deposited on the left-hand end of the drum before pin-shifting movement started two of such wires would intervene between the 25 normal Fig. 11 and shifted Fig. 14 position of each of the more closely spaced shift-pins 51a, 51b, etc. The pin 51a would engage the wire to the left of it, deposit that wire in the slot of the twister gear 41b and then continue to engage 30 the next wire 65 and deposit it in the gear 41a. Similarly, the pin 51b would engage the wire to the left of it, deposit such wire in the slot of the twister gear 51c, and would then continue 35 onward into association with the slot of the twister gear 41b. Such action of the pins in depositing mesh wires in the wrong gear-slots would result in a disarranged mesh-wire pattern and would probably cause wire-breakage. For this reason the mesh wires entering into the fine-40 mesh portion of the fabric are not fed on to the drum surface until after shifting movement of the pins 51 has progressed to an extent (shown in Fig. 12) such that the pin 51a has passed beneath the mesh wire 65 which is to be deposited 45 in the slot of the twister gear 41b by the succeeding pin 51b. Fig. 13 illustrates a pin-position intermediate those of Figs. 12 and 14, and shows all pins as they begin to deposit the mesh wires 65 in the respectively associated twister gears.

50 Figs. 15 and 16 are developed views illustrating successive positions of a pair of leftwardly moving shift pins 51a associated with one row of twister gears and of two pairs of rightwardly moving shift pins 51b and 51c associated with 55 the next row of twister gears. In Fig. 15, the shift pins 51c have engaged a mesh wire 65 and have moved it slightly to the right, while the pins 51a of the next following set have progressed far enough to the left to just pass that mesh wire. 60 Since the pins 51a are to clear the wire engaged by the pins 51c, it will be obvious that such mesh wire can not enter into association with the drum until after the leading pin 51a has, in the rotation of the drum, passed the point indicated by 65 the line M.

70 In Fig. 16, the drum has progressed in its rotation to a point where the pins 51b and 51c have deposited the mesh wires respectively associated with them in the slots of the associated 75 twister gears 41b and 41c, and the shift pins 51a of the next succeeding set are in the position shown. As will again be obvious, the mesh wires 65 shown in Fig. 16 must have entered into association with the drum by the time the leading pin 51a reaches the point in drum-rotation in-

5 indicated by the line N, as otherwise that pin, and the other leading pins of the same set, would pass beneath and not engage the mesh wires which they are to shift.

Shift pins forming the fabric-portion of next 5 coarser mesh are shown in Fig. 17. In full lines are shown a pair of shift pins 51g in their normal position and also a pair of pins 51h of the next set in advance, the latter having started 10 their rightward shifting movement. As is clear 10 from Fig. 17, only one mesh wire 65 intervenes between the normal position of the pins 51g and the slot in the twister gear 41g into which those pins are to deposit such wire. As a result, the mesh wires 65 entering into this portion of the 15 fabric may be deposited upon the drum when the pins 51 are in their normal positions.

20 The dotted-line showing of Fig. 17 illustrates the positions of the two pairs of pins 51h and 51g at an intermediate point in their shifting 20 movement. The pins 51h have carried the wire 65 associated with them almost into the slot in the twister gear 41h, while the leading pin 51g is about to engage that wire. This mesh wire must be in association with the drum by the 25 time the leading pin 51g, in the rotation of the drum, reaches the point indicated by the line P, as otherwise that pin would fail to engage the mesh wire and deposit it in the slot of the gear 41g. Therefore, while the mesh wires with which 30 such pins as 51g and 51h are to co-operate may enter into association with the drum while those pins are in their normal positions they must enter into association with the drum before the leading pins reach the point indicated by the 35 line P.

40 In the arrangement shown in Figs. 15 to 17, the line P lies between the lines M and N; and, as a result, the mesh wires entering into the two finest mesh-portions of the fabric may all be fed 45 on the drum at the same point, entering into association with the drum between the lines M and P as shown in Fig. 18. In the particular machine shown and described in this application, this method of feeding the mesh wires is employed, the mesh wires entering into the two coarser-mesh portions of the fabric being fed on to the drum through guide tubes 66 supported in a bar 67 extending across the front of the machine; while the remainder of the mesh wires 50 are fed on to the drum through guide tubes 68 mounted in a bar 69 which also extends across the front of the machine, the bar 69 being spaced from the bar 67 in the direction of drum rotation, as is clear from Fig. 3. Since, as above indicated, the mesh wires which are to be shifted by the pins 51g and 51h may enter into association with the drum while the shift pins are in their normal position, those mesh wires might be fed on to the drum through guide tubes 66 in the 55 bar 67. If the extent of variation in mesh width is greater than that in the specific example contemplated in this application, it may be advisable, if not necessary, to feed mesh wires into association with the drum at three or more points 60 rather than at only two points, as indicated. In any case, the principles embodied in the above 65 description of Figs. 15 to 18 will guide in determining where any given set of mesh wires is to enter into association with the drum.

70 After any set of pins has reached the limit of its movement in forming the mesh-pattern and creating the slack above referred to they are retracted slightly, each of the cam-grooves 55 and 55' being provided with an inwardly in- 75

clined portion C—D for the purpose of effecting such retraction. The movement of the pins 51 effected by the cam-groove portions C—D carries the pins out of association with the slots in the respective twister gears and opens those slots for the deposition of the line wires 75, which are fed from the rear of the machine over guide rollers 76 and deposited directly in the twister-gear slots. During this deposition of the line wires, 10 the cam-followers 54 and 54' occupy dwells D—E in the cam-grooves 55 and 55'.

The length of each dwell B—C in the pin-shifting cams is desirably such that two, and preferably three, sets of shift pins occupy their 15 advanced positions simultaneously. Otherwise, each advancing set of shift pins might, by the tension it creates in the mesh wires, draw out the slack created by the preceding set.

After the line wires have been deposited in the 20 twister-gear slots, the shift pins 51 are again returned to their advanced position by outwardly inclined portions E—F in the cam-grooves 55 and 55'. This movement of the pins creates in the line wires substantially the same amount of 25 slack as that already existing in the mesh wires. If necessary each cam-groove may be provided with a dwell at the point F in order to prevent the slack created by one set of pins from being pulled out by the next succeeding set of pins.

30 Preferably, two line wires 75 are provided at the edges of the fabric, as indicated in Figs. 8 and 9. Each pair of these border wires will occupy alternately twister gears which contain a mesh wire and twister gears which contain no 35 mesh wire. To create slack for the twisting operation performed by each of the latter gears, each leftwardly moving pair of shift rods carries at their right-hand ends an extra pair of pins 51 $\frac{1}{2}$ which play no part in the shifting of the 40 mesh wires. Similarly, the pins 51 $\frac{1}{2}$ at the left-hand ends of each rightwardly moving pair of shift rods shift no mesh wires and are provided merely for the purpose of creating slack in the line wires. Obviously, if single instead of double 45 border wires were used, such extra pairs of pins might be eliminated.

Immediately beyond the outwardly sloping cam-groove portions E—F, the cam-grooves 55 and 55' are provided with inwardly sloping portions F—G each of which leads into a dwell. As 50 a result of the presence of the inwardly sloping cam-groove portions F—G, the shift pins are retracted a slight distance to bring their bases into positions corresponding to the location of the 55 corners in the finished mesh.

Following the dwell beginning at G, each of the cam-grooves 55 and 55' contains in order a short inwardly inclined portion H—I, a dwell I—J, and a second inwardly inclined portion J—K. The 60 axial extent of each cam-groove portion H—I is sufficient to move the shift pins 51 out of alignment with the slots in the associated twister gears and to uncover those slots so that the wire-locks can be withdrawn therefrom when the fabric is 65 stripped from the drum. The inclined portion J—K of each of the cam-grooves 55 and 55' restores the shift rods 50 and pins 51 to the normal positions they occupy before beginning their mesh-forming movement.

70 While the shift rods 50 and pins 51 have been progressing through the series of mesh-forming movements illustrated in Fig. 4, the cam-followers 59 and 59' have been occupying dwells in the cam-grooves 60 and 60', such dwells terminating at the point indicated at R in Fig. 5.

Beyond the point R, each of the cam-grooves 60 and 60' slopes outwardly to the point S. These outwardly inclined portions R—S of the cam-grooves cause the racks 46 to move axially outwardly of the drum and to rotate the twister 5 gears. This rotation of the twister gears twists the line wires and mesh wires together, takes up the slack created in the mesh wires and line wires, and draws the mesh wires tightly against the bases of the pins 51. Because the pins 51 are 10 located at the corners of the mesh, no distortion of the mesh can result from the twisting operations.

At the conclusion of the lock-forming operation the wires are under stress, as a result of 15 their inherent elasticity; and this stress is reflected in a tendency of the wires of each lock to untwist and bear against the sides of the slot in the associated twister gear with sufficient force to create an appreciable amount of friction 20 opposing withdrawal of the locks from the twister-gear slots when the finished fabric is stripped from the drum. To overcome this, I make the portions R—S of the rack-actuating cam-grooves 60 and 60' sufficiently long to carry the slots in 25 the twister gears slightly past their vertical position; and beyond the portion R—S, I provide each of the cam-grooves 60 and 60' with a short inclined portion S—T which rotates the twisting gears in a retrograde direction and restores the 30 slots therein to their normal vertical position. The extent of this retrograde rotation of the twister gear is just sufficient to relieve the mesh wires and line wires of the stress which has caused them to bear against the sides of the 35 twister-gear slots and thereby frees the wire-locks so that they can readily be removed from such slots when the fabric is stripped from the drum.

Beyond the point T, each of the cam-grooves 40 60 and 60' is provided with a dwell T—U leading into an inwardly inclined portion U—V which, in turn, leads into the dwell terminating at R.

The circumferential disposition of the cam-grooves 60 and 60' relative to the cam-grooves 45 55 and 55' is illustrated in Fig. 5, from which it will be apparent that the dwell V—R in each of the cam-grooves 60 and 60' lies opposite the portion A—G of each of the cam-grooves 55 and 55'; that the portion R—S of each of the grooves 50 60 and 60' lies opposite each of the dwells G—H in each of the cam-grooves 55 and 55'; and that the dwells T—U circumferentially overlap the dwells I—J.

The finished fabric is stripped from the drum 55 at a point located within the overlapping portions of the dwells T—U and I—J. To effect the stripping operation, the finished fabric passes over a stripping roll 80 (Fig. 3) mounted on a shaft 81 (Figs. 1 and 2) extending across the front of 60 the machine. At one end, the shaft 81 projects beyond the frame 21 and has rotatably mounted upon it a sprocket 82 operatively connected by a chain 83 to a second sprocket 84 which is rotatable with the shaft 33. The sprocket 82 is 65 connected to the shaft 81 through a friction clutch 85 which is capable of slipping when subjected to a maximum predetermined torque.

On the face of the stripping roll 80 I provide an annual series of rows of projections 90 conveniently in the form of a U-shaped staples mounted in holes in the stripper roll. The spacing of the staples 90 in each row corresponds to the graduated width of the mesh, each staple being so located that it will be received in an 75

acute-angle corner of the mesh pattern, as is clear from Fig. 10.

The speed ratio of the stripper-roll drive 82—83—84 is such as would, in the absence of slipping in the clutch 85, impart to the stripper roll 80 a peripheral speed somewhat in excess of the peripheral speed of the drum upon which the fabric is formed. As a result, the staples 90 are drawn tightly into the corners of the mesh of the fabric and serve to pull the locks of the fabric out of the slots in the twister gears and to cause the fabric to leave the drum.

After leaving the stripper roll 80, the fabric passes over an idler roll 92 and thence to take-up mechanism 95.

In setting up the machine for operation, the mesh wires are led through their respective guide tubes 66 and 68, the line wires are led over the guide rollers 76, and the free ends of both mesh wires and line wires are secured to the drum, as by wrapping them about pins 51. To prevent wastage of the line wires, the mesh wires may be attached first, the drum then rotated until the free ends of the mesh wires have just passed the guide rollers 76, and the line wires then attached. Thereafter, as the drum is rotated, the mesh wires will be deflected into the proper pattern and deposited in the twisted gears, the line wires will then be deposited in the twister gears, and the twister gears operated to form the locks in the fabric. As an incident to their mesh-forming advance from normal position, the shift pins 51 create slack in the mesh wires, and on their second advance they create slack in the line wires, such slack being taken up when the line wires and mesh wires are twisted together by the twister gears. Prior to the operation of the twister gears, the shaft pins 51 have been retracted to positions corresponding to the obtuse-angled corners of the mesh pattern; so that the action of the twister gears in drawing the wires tight will pull the wires against the pins 51 and will not distort the mesh pattern.

As the leading end of the fabric reaches the stripper roll 80 it is led over that roll, around the idler 90, and to the take-up mechanism 95. Prior to the stripping operation, the pins 51 have been retracted out of the mesh-corners so that the stripping operation will not be opposed by friction between the wires and the pins. This further retraction of the pins is necessary where the pins occupy inclined positions, as in the machine illustrated in the drawings, but is of advantage in facilitating stripping even if the pins are normal to the drum-surface.

The finished fabric, after being stripped from the drum by the stripper roll, is wound into a stock roll on the arbor of the take-up mechanism; and when the stock roll reaches the desired size, the machine is stopped, the fabric cut transversely between the stock-roll and the idler roller, and the stock roll is removed from the machine.

I claim as my invention:

1. In a machine for making straight-line wire fabric having a mesh of graduated width, a movable carrier, a plurality of lock-forming devices mounted on said carrier and arranged in rows both in the direction of carrier movement and transversely thereof, means for feeding mesh wires to said carrier in planes between the former rows of lock-forming devices, and mechanism for deflecting each mesh wire laterally of itself and depositing it alternately in the lock-forming devices of the rows between which it is fed, said mechanism comprising a pair of shift rods

mounted on said carrier on opposite sides of each transverse row of lock-forming devices and interconnected for joint movement parallel thereto, means for successively shifting said pairs of shift rods alternately in opposite directions from a normal position to a shifted position and returning them to normal position as the carrier moves, each of said shift rods being provided with a series of wire-engaging abutments disposed thereon to be in association with the respective lock-forming devices of the associated transverse row thereof when in shifted position, the means for feeding mesh wires being arranged to feed mesh wires for the coarse-mesh portion of said fabric into association with said abutments at a point at a point in carrier movement where said abutments are in normal position and to feed mesh wires for the fine-mesh portion of said fabric into association with said abutments at a point in carrier movement where the associated abutments are in an intermediate position such that only one of said latter mesh wires will intervene between each abutment and its shifted position.

2. The invention set forth in claim 1 with the addition that said carrier is a rotatable drum, the means for guiding said mesh wires comprising a set of guides for the mesh wires entering into the coarse-mesh portion of the fabric and a second set of guides for the mesh wires entering into the fine-mesh portion of the fabric, the second set of guides being spaced from the first set in the direction of rotation of said drum.

3. The invention set forth in claim 1 with the addition that each of said abutments, when moved from normal to shifted position, travels a short distance beyond its associated lock-forming device to create slack in the mesh wire it engages.

4. In a machine for making straight-line wire fabric, a movable carrier, a plurality of lock-forming devices mounted on said carrier and arranged in rows both in the direction of carrier movement and transversely thereof, means for feeding mesh wires to said carrier in planes between the former rows of lock-forming devices, and mechanism for deflecting each mesh wire laterally of itself and depositing it alternately in the lock-forming devices of the rows between which it is fed, said mechanism comprising a pair of shift rods mounted on said carrier on opposite sides of each transverse row of lock-forming devices and interconnected for joint movement parallel thereto, each of said shift rods being provided with a series of wire-shifting abutments spaced thereon at intervals corresponding to the spacing of the lock-forming devices in the associated row thereof, and means for successively shifting said pairs of shift rods alternately in opposite directions from a normal position, in which each abutment lies on the opposite side of a mesh wire from the lock-forming device into which such wire is to be deposited, and a shifted position, in which each abutment has deposited the mesh wire it shifts in the proper lock-forming device and has continued onward for a short distance to create slack in such wire, said means operating thereafter to restore the shift-rods to normal position.

5. In a machine for making straight-line wire fabric, a movable carrier, a plurality of lock-forming devices mounted on said carrier and arranged in rows both in the direction of carrier movement and transversely thereof, means for feeding mesh wires to said carrier in planes between the former rows of lock-forming devices,

mechanism for deflecting each mesh wire laterally of itself and depositing it alternately in the lock-forming devices of the rows between which it is fed, means for feeding line wires to said drum and depositing them in said lock-forming devices above said mesh wires, means for actuating the lock-forming devices after the mesh wires and line wires have successively been deposited therein, and a stripping device for stripping the finished fabric from the carrier, said wire-deflecting mechanism comprising two series of wire-shifting abutments between adjacent transverse rows of lock-forming devices, and means acting as said carrier moves first to advance said abutments from their normal positions to deposit the mesh wires and create slack therein, next to retract the abutments to permit the line wires to be deposited in the lock-forming devices, next to advance the abutments to create slack in the line wires, next to retract the abutments and hold them in positions corresponding to the corners of the mesh in the fabric while said lock-forming devices are being actuated, next to retract the abutments further and to hold them out of the corners of the mesh while the fabric is being stripped from the carrier, and last to restore the abutments to their normal positions.

6. In a machine for forming wire fabric having mesh wires, a plurality of parallel rows of lock-forming devices, and mechanism for deflecting mesh wires alternately in opposite directions and depositing them in said lock-forming devices, said mechanism comprising wire-engaging abutments and means for moving said abutments parallel to said rows of lock-forming devices to engage the mesh wires, to shift the mesh wires and deposit them in the lock-forming devices, and to continue beyond wire-depositing position to create slack in the mesh wires.

7. In a machine for forming wire fabric having mesh wires, a plurality of parallel rows of lock-forming devices, mechanism for deflecting mesh wires alternately in opposite directions and depositing them in said lock-forming devices, said mechanism comprising wire-engaging abutments, and means for advancing said abutments to cause them to shift mesh wires and deposit them in the lock-forming devices and for then retracting said abutments to positions corresponding to the corners of the mesh in the fabric, and means for actuating said lock-forming devices while said abutments are in such retracted positions.

8. In a machine for forming wire fabric having mesh wires, a plurality of parallel rows of lock-forming devices, wire-engaging members disposed between adjacent rows of lock-forming devices, said members being movable parallel to said rows, means for actuating said lock-forming devices, and mechanism for holding said members in positions corresponding to the corners of the mesh in the fabric while the lock-forming devices are being actuated and for subsequently retracting them out of such corners, and means operative when said members are so retracted for stripping the fabric from the lock-forming devices.

9. In a machine for making wire fabric, a movable carrier, means for moving said carrier, a plurality of lock-forming devices mounted in the face of the carrier in positions corresponding to the location of locks in the mesh pattern of the fabric the machine is to produce, means for depositing wires in mesh pattern in said lock-forming devices as said carrier moves, mechanism for actuating said lock-forming devices, a stripper roll over which the fabric passes after the locks there-

in are formed, said stripper roll being provided with projections positioned on the face thereof to engage the fabric in corners of the mesh pattern, and means tending to drive said stripper roll at a peripheral speed greater than the linear speed of 5 said carrier.

10. In a machine for making wire fabric, a movable carrier, means for moving said carrier, a plurality of lock-forming devices mounted in the face of the carrier in positions corresponding 10 to the location of locks in the mesh pattern of the fabric the machine is to produce, means for depositing wires in mesh pattern in said lock-forming devices as said carrier moves, mechanism for actuating said lock-forming devices, a stripper 15 roll over which the fabric passes after the locks therein are formed, and means tending to drive said stripper roll at a peripheral speed greater than the linear speed of said carrier.

11. In a machine for making wire-fabric, a 20 movable carrier, means for moving said carrier, means for feeding wires to said carrier, means on said carrier for deflecting at least some of said wires and twisting the wires together to form a fabric, a stripper roll for stripping finished fabric 25 from the carrier and having on its faces projections positioned to engage in apices of the mesh, and means tending to drive said stripper roll at a peripheral speed greater than the linear speed of said carrier.

12. In a machine for making straight-line wire fabric having a fine-mesh portion and a coarse-mesh portion, the width of the former being less than half the width of the latter, a movable carrier, an endless series of parallel shift-members 35 each extending across said carrier transversely to the direction of movement thereof, wire engaging abutments on said shift members, means for successively moving said shift-members alternately in opposite directions to deflect the mesh wires 40 into the mesh pattern as said carrier moves, a set of guides for mesh wires entering into the coarse-mesh portion of the fabric, and a second set of guides for mesh wires entering into the fine-mesh portion of the fabric, said second set of 45 guides being spaced from said first set in the direction of carrier movement whereby the wires they guide will enter into association with said abutments after wire-deflecting movement of said shift members has begun.

13. In a machine for making a graduated-mesh wire fabric in which the width of the narrowest mesh is less than half that of the coarsest mesh, a movable carrier, an endless series of transverse rows of lock-forming devices mounted on said carrier, mechanism for deflecting mesh wires laterally into the mesh pattern and for depositing the deflected mesh wires in the lock-forming devices of successive rows thereof as said carrier moves, said mechanism comprising rows of wire-engaging abutments spaced at intervals corresponding to the spacing of the lock-forming devices, means for imparting wire-deflecting movement to said abutments, and means for feeding two different sets of mesh wires to said carrier at 60 spaced points in carrier movement, said means being so arranged that the more advanced set of mesh wires do not enter into association with said abutments until after the other set of mesh wires have been partially deflected.

14. The invention set forth in claim 12 with the addition that said abutments are mounted on said carrier.

15. In a machine for making wire-fabric having a mesh of graduated width, a movable carrier, a 75

lock-forming device on said carrier, a wire-shifting abutment on said carrier and shiftable transversely of the direction of carrier movement from a normal position to a shifted position in which it is in association with said lock-forming device, means for feeding two mesh wires to said carrier at spaced points between the normal position and the shifted position of said abutment, and means for shifting said abutment from normal to shifted position as said carrier moves, said shifting means acting before said two mesh wires are fed to said carrier to move said abutment to a position between them.

16. In a machine for making wire-fabric having a mesh of graduated width, a movable carrier, a wire-shifting abutment on said carrier and shiftable transversely of the direction of carrier movement from a normal position to a shifted position, means for feeding two mesh wires to said carrier at spaced points between the normal position and the shifted position of said abutment, and means for shifting said abutment from normal to shifted position as said carrier moves, said shifting means acting before said two mesh wires are fed to said carrier to move said abutment to a position between them.

17. In a machine for making wire-fabric, a pair of twister-gears each having a radially extending slot for receiving wires which are to be twisted

together by gear-rotation, and means supporting said twister gears on spaced, parallel axes, said gears being respectively provided with annular series of gear teeth spaced axially from each other and overlapping radially.

18. In a machine for making a graduated-mesh wire fabric in which the width of the narrowest mesh is less than half that of the coarsest mesh, an endless series of parallel rows of lock-forming devices, a movable carrier, mechanism including wire-shifting abutments mounted on said carrier for deflecting mesh wires into the desired mesh pattern and for depositing the deflected mesh wires in the lock-forming devices of successive rows thereof as said carrier moves, said abutments being arranged in rows extending transversely of said carrier with the abutments in each row spaced at intervals corresponding to the spacing of the lock-forming devices, means for imparting wire-deflecting movement to said abutments, and means for feeding two different sets of mesh wires to said carrier at spaced points in carrier movement, said means being so arranged that the more advanced set of mesh wires do not enter into association with said abutments until after the other set of mesh wires have been partially deflected.

HARRY L. KITSELMAN.
